VANED AIR DISTRIBUTOR FOR INTERNAL COMBUSTION ENGINE STARTING AIR

George Steven, Kenmore, N. Y., assignor to Worthington Corporation, Harrison, N. J., a corporation of Delaware

Application September 16, 1953, Serial No. 380,562

4 Claims. (Cl. 60—16)

This invention relates to internal combustion engines which are started by high pressure air and more particularly to a distributor for timing and distributing the delivery of the starting air to the cylinders of an engine in proper time sequence to initiate starting of the engine.

An object of the present invention is to provide a starting air distributor for internal combustion engines which is automatically brought into operation upon the turning on of the starting air supply to the engine, operates to distribute such starting air in proper time sequence to the engine cylinders, and is automatically disconnected during operation of the engine thereby relieving the starting air distributor of wear development on parts thereof normally occasioned by continuous engine operation. With this and other objects in view, as may appear from the accompanying specification, the invention consists of various features of construction and combination of parts, which will be first described in connection with the accompanying drawings, showing a vanned air distributor for internal combustion engine starting air of a preferred form embodying the invention, and the features forming the invention will be specifically pointed out in the claims.

In the drawings:

Figure 1 is a longitudinal section through the improved air distributor, taken on line 1—1 of Figure 2.

Figure 2 is a cross-section through the air distributor taken on the line 2—2 of Figure 1.

Figure 3 is a fragmentary vertical section through a part of an internal combustion engine showing one form of starting air valve structure with which the improved distributor cooperates.

Figure 4 is a fragmentary vertical section through an internal combustion engine showing another form of starting air inlet structure to the engine cylinder, with which the improved starting air distributor cooperates.

Referring more particularly to the drawings, the improved starting air distributor for internal combustion engines comprises a casing 1 which is formed of an inlet section 2, a distributing section 3 and a shaft coupling enclosure section 4 which may be attached to any suitable support. An operating timing shaft 5 is rotatably carried by the section 4 of the housing 1 and the shaft 5 is to be connected to the cam shaft or crank shaft (not shown) of an internal combustion engine for rotation therewith.

The intermediate or distributor section 3 of the housing 1 has a plurality of circumferentially spaced starting air ports 6 therein each of which connects with an individual cylinder of an internal combustion engine through separate outlet passages 7 in various ways, two forms of which are hereinafter described in connection with Figures 3 and 4 of the drawings. The distributor section or plate 3 is held stationary through the connection of the housing sections 2, 3 and 4. A shaft 8 is rotatably carried by a suitable bearing structure 9a and 9' attached to the stationary distributor section 3 and the enclosing section 4. The distributor ports 6 communicates with the

2

space 9 within the interior of the inlet section 2 of the housing 1 and starting pressure air enters the space or chamber 9 through a tangential inlet opening 10.

A distributing rotor 11 is keyed or otherwise attached to the shaft 8 for rotation therewith and it has a plurality of radial arcuate vanes 12 formed on its face outwardly of the distributor plate or section 3. The rotary distributor 11 has a single port 14 extending therethrough which is brought into communication successively with the ports 6 during rotation of the distributor 11 to permit the passage of starting air from the space or chamber 9 through the rotary distributor 11, port 6 into the passage 7 and thence to the cylinders of the engine. There is a clearance between the lateral side of each vane 12 and the end wall of the distributor housing, so that an air jet entering through air port 10 and striking blades 12 will be free to escape through port 14 and over the passages 7, so the distributor may operate on the turbine principle. The rotary distributor 11 is urged outwardly away from the stationary plate 3 by a spring 15 which breaks the connection between the shafts 5 and 8 when starting air pressure is turned off. The shafts 5 and 8 are provided with cooperation clutch sections 16 at their adjacent ends as clearly shown in Figure 1 of the drawings.

When it is desired to start an internal combustion engine equipped with the improved starting device, the starting air is turned on and this starting air under pressure enters the space or chamber 9 in the inlet section 2 of the housing and has a tendency to move the rotary distributor 11 towards the facing surface of the stationary distributor section 3 against the tension of the spring 15. However, at such time, the clutch sections 16 may be out of alignment which will prevent connection of the shafts 8 and 5 for providing the proper time distribution of the starting air. The starting air entering the chamber 9 through the inlet passage 10, tangentially to the circumference of the rotary distributor 11 will act upon the blades 12 and rotate the rotary distributor 11 and the shaft 8 and at such time as the two clutch sections 40 are brought into proper connecting relation by this rotation the pressure of the air will force the shaft 8 into coupled connection with the time shaft 5 and thus the flow of the starting air through the passageway 14 and ports 6 will be properly timed in accordance with the sequence of operation of the engine cylinders. After the port 14 has passed the respective port 6 and cut off the flow of pressure air into the respective passage 7, and the proper operation of the respective cylinder of the engine has occurred some residue pressure air may remain in the passage 7 connected thereto. However, provision is made to bleed such residue pressure air to atmosphere by means of a port 31 formed in the distributor plate 3. The port 31 opens into the passageway 7, and is closed by the rotary distributor 11 when the ports 6

50 are open to receive pressure air therethrough. The rotary distributor 11 has a channel 32 in its inner face, which during rotation of the distributor establishes communication between the port 31 and the passage 17 through the stationary distributor plate to allow any residual pressure air to flow from the passage 7 into the chamber 18 formed in the housing section 4, and to atmosphere through the bleed-off opening 19.

Figure 3 of the drawings shows a form wherein the starting air to the engine cylinders enters the head of the engine through a starting air passageway 33 which is normally blocked by a starting air check valve 34 held closed by a spring 20. A piston 21 is mounted on the stem 29 of the valve 34 and starting air from the distributor passage 7 is delivered against the piston 21 in opposition to the tension of the spring 20 through a suitable pipe 22, and thus when the starting air distributor, shown

in Figures 1 and 2 of the drawings, is in proper time operation through the coupling connection of the shafts 8 and 5 starting pressure air will be admitted against the piston 21 which will force the valve 34 off its seat and permit the pressure starting air from passageway 33 to enter the cylinder 23 of the engine and operate the piston and, consequently, the engine until such time as the normal operation of the engine is established. The starting air is then turned off.

In the construction shown in Figure 4 of the drawings, the piston 21 on the stem of the starting air valve is eliminated and the starting air valve 24 is held seated by means of a spring 25. Pressure air is delivered from one of the air passages 7 in the distributor in properly timed relation to one cylinder of a multi-cylinder engine, for starting the engine, through a pipe 26. The pressure of such air overcomes the tension of spring 25 and opens valve 24 to admit starting air to the cylinder 27. In multiple cylinder engines similar pipes 26 lead to each cylinder from the corresponding air passage 7 in the distributor.

When the flow of starting air to the distributor is cut off, the consequent pressure against the rotary distributor urging it against the tension of the spring 15 will, of course, be relieved and the spring will act to disconnect the shafts 5 and 8 so that the rotary distributor 11 will remain stationary during the normal operation of the engine thus relieving this distributor of wear developed during operation of the engine.

It will be understood that the invention is not to be limited to the specific construction or arrangement of parts shown, but that they may be widely modified within the invention defined by the claims.

What is claimed is:

1. In a starting air distributor for internal combustion engines, the combination with an engine rotated shaft, of a starting air distributor shaft, means for disengagably connecting said shafts for unitary rotation, an air distributor disc rotatable with said distributor shaft, means for mounting said rotary distributor disc to be movable longitudinally under pressure of starting air to establish rotating connection between said engine-rotated shaft and said distributor shaft upon application of engine starting pressure air to said rotary distributing disc, means for disengaging said shafts upon the cutting off of application of starting air pressure to the distributing disc, a housing enclosing said rotary distributor disc, said housing having an air inlet for starting pressure air opening therewith tangentially of the circumference of said disc, and a plurality of arcuate vanes carried by said disc and engaged by said pressure air entering the casing for rotating the disc.

2. In a starting air distributor for internal combustion engines, the combination with a multiple cylinder for internal combustion engines including starting air passages opening into the cylinders and check valves in said passages, and a shaft rotated during rotation of the engine, of a starting air distributor shaft, means for connecting said shafts for unitary rotation, means normally urging said shaft out of connection, an air distributor disc rotatable with said distributor shaft, a housing enclosing said rotary distributor disc and provided with a pressure air receiving space, means for mounting said distributor shaft and said rotary distributor disc to be movable longitudinally under pressure of air in said

space to connect said distributor shaft with said engine rotated shaft, a stationary distributor plate provided with ports and passages corresponding to the respective cylinders of the engine, said rotary distributor disc provided with an air port which is moved successively into communication with the ports in the stationary distributor plate when said shafts are connected for unitary rotation, said housing provided with an inlet for starting pressure air opening therewith tangentially of the circumference of said disc, and a plurality of arcuate vanes carried by said disc and engaged by pressure air entering the casing for rotating the disc.

3. In a starting air distributor for internal combustion engines, the combination with an engine rotated shaft, of a starting air distributor shaft, means for disengagably connecting said shafts for unitary rotation, an air distributor disc rotatable with said distributor shaft, means for rotating said disc and distributor shaft, means for mounting said rotary distributor disc to be movable longitudinally under pressure of starting air to establish rotating connection between said engine rotated shaft and said distributor shaft upon application of engine starting pressure air to said rotary distributing disc, means for disengaging said shafts upon cutting off of application of starting air pressure to the distributing disc, a stationary distributor plate provided with ports and passages corresponding to the respective cylinders of a multiple cylinder internal combustion engine, said rotary distributor disc provided with an air port which is moved successively into communication with the ports in the stationary distributor when said shafts are connected for unitary rotation, a housing enclosing said distributor disc, said housing having an inlet for starting pressure air opening therewith tangentially of the circumference of said disc, and a plurality of arcuate vanes carried by said disc and engaged by pressure air entering the casing for rotating the disc.

4. In combination with an internal combustion engine having an engine-rotated shaft, an air distributor, an axially movable distributor shaft mounted therein, a rotor fixed on said shaft, vane means disposed on said rotor, means for detachably connecting said distributor shaft to said engine shaft for rotation therewith, means normally maintaining said shafts disengaged from one another, means for supplying starting air to said distributor to impinge against said vane means to rotate said distributor shaft and move it axially of the distributor to connect it to said engine shaft for rotation therewith, air passage means in said distributor for passing air therethrough to said internal combustion engine, said rotor having an air port therein in communication with said air supply means for receiving air therefrom and in communication with said air passage means for discharging starting air therethrough.
